UNITED STATES PATENT OFFICE.

ALEXANDER SHIELS, OF GLASGOW, SCOTLAND.

VACUUM OR SUCTION PUMP.

SPECIFICATION forming part of Letters Patent No. 592,888, dated November 2, 1897.

Application filed February 3, 1896. Serial No. 577,861. (No model.) Patented in England February 25, 1895, No. 3,979.

To all whom it may concern:

Be it known that I, ALEXANDER SHIELS, M. B., C. M., B. Sc., a subject of the Queen of Great Britain, and a resident of the city of 5 Glasgow, Scotland, have invented certain new and useful Improvements in and Connected with Vacuum or Suction Pumps, (patented in Great Britain, No. 3,979, dated February 25, 1895,) of which the following is a specification.

This invention relates to vacuum or suction pumps; and it has for its object to improve their construction.

In order that my said invention may be 15 properly understood, I have hereunto appended two explanatory sheets of drawings, whereon—

Figure 1 is a vertical cross-section of the pump. Fig. 2 is a view of the fly-wheel to a 20 reduced scale, and Fig. 3 is a longitudinal section of the foundation. Fig. 4 is a longitudinal section, and Fig. 5 a plan, of the automatic valve for drawing off excess oil from the pump-barrel.

25 Referring to the drawings, in carrying out my invention I use, as usual, a cylinder or barrel *a*, in which works the pump-bucket *b*. This barrel is fitted on a hollow foundation *c*, having a suction passage-way or duct *d* open

30 at one end *d'*, where it communicates with the tank, vessel, or such like in which it is desired to create a vacuum or from which it is desired to exhaust a part or the whole of the contained air or fluid, and closed at the 35 other end, where it communicates with the barrel of the pump, by an automatically-acting valve *e*. This valve *e* consists of a guided spindle *f*, provided with two metal disks *g* *h* at its upper end, between which a

40 leather or rubber washer, ring, or disk *i* is secured in such manner as to serve as the valve-face. The disk *g* can, as shown, be made in one with the spindle *f*, while the disk or washer *h* is held in place by the screw-nut *j*. A metal ring *k*, with an upwardly-projecting ledge or ridge *k'* on it, which serves as the valve-seat, is secured in the foundation. This ring is made to support, by means of arms *k*², the guide *l* for the valve-spindle.

45 50 The top *c'* of the foundation *c*, which also serves as the bottom of the barrel of the pump, is slightly convexed, so as to cause any excess

of oil or the like to run down toward the edge or circumferential rim of the bottom of the barrel, where it collects in a groove *c*² 55 and can be drawn off by means of an automatically-acting valve arrangement, herein-after described.

The bucket is formed into two parts *m* *n*, bolted or screwed together, the upper part 60 forming a ring with a central upwardly-projecting cylinder *m'* on it and the lower part forming a ring or disk which serves as the bottom or face plate of the bucket. These parts, which fit and work in the cylinder or 65 barrel of the pump, have secured between them a ring *o*, of leather or rubber, which is so bent or shaped as to work tightly against the interior walls of the barrel in the same manner as an ordinary cup-leather. The lower 70 plate *n* carries in its central aperture a ring-seat *n'*, having a raised edge or projection on it.

Fitted in a guide *p* in a bridge *q*, extending across the cylindrical portion *m'* of the bucket *b*, is a spindle *r*, having a slightly-larger valve *s* of the same construction as the 75 automatic valve *e*, hereinbefore referred to. The rubber or leather face *s'* of this valve works against the aforesaid ring-seat *n'*, fitted in the plate *n*.

80 *t* are screw-nuts for securing the guide *p*. *u* is the fork, and *u'* the pivot-pins, of the plunger, secured in place by the taper-pins *u*².

v is the driving-crank, and *v'* the connecting or pump rod.

85 *w*² are the standards, fitted in sockets in the foundation.

w is a stop-ring for limiting the movement of the spindle *f*.

The arrangement is such that at the up-stroke of the plunger the upper bucket-valve *s* by its own weight, combined with the suction at its under side, is held close against its seat, while the lower valve *e* is raised off its seat. At the downstroke, on the contrary, 95 the upper valve *s* lifts off its seat, while the lower valve closes.

In order to lessen noise and cushion the action of the valves, suitable cushions *x*, of rubber or such like, may be provided on either 100 the guides or the valves.

In some cases, if desired, a spiral or helical spring can be used to press the upper valve to its seat.

The automatic-valve arrangement shown at Figs. 4 and 5 for drawing off excess of oil from the pump-barrel consists of a cored-out metal piece z , which may be provided with 5 a cut-off plug-tap z' and delivery-nozzle z'' at one end. In the center of the metal piece is an automatically-acting lift-valve z^3 , so arranged and fitted, as shown, that at the downstroke of the plunger or bucket it opens upward off 10 its seat z^4 and allows oil to escape, while at the upstroke it closes down on its seat and prevents ingress of air. z^5 is an internal 15 guide-plug.

In order to balance the working parts and 15 to utilize the action of the vacuum at the under side of the bucket or plunger of the pump when it is on its downstroke, I prefer to fit on the crank-shaft a fly-wheel y , which at the side nearly opposite to the crank is weighted 20 or is provided with a weight, as at y' .

Having now fully described my invention, what I claim, and desire to secure by Letters Patent, is—

1. In combination in an air-pump, a foundation having a depressed cavity or duct, with 25 a bracket depending therein, a valve guided in said bracket, the barrel mounted on the foundation, the bucket having a cylindrical portion with a flange m extending laterally 30 around its lower part, the ring n secured to the flange and holding interposed packing, the ring n' also held by the said ring n and the bucket and projecting inwardly there-

from, the valve guided within the bucket and resting on the inwardly-projecting ring n' and 35 means for operating the bucket, substantially as described.

2. In combination, the foundation with its valve, the bucket of cylindrical form having a flange projecting laterally about its lower 40 portion, the valve within the bucket and the ring fitting against the lower part of the bucket, and the removable packing and valve-seat ring, one projecting outwardly and the other projecting inwardly from the bucket, 45 both of said parts being held by the said ring n , substantially as described.

3. In combination, the barrel, the foundation with its valve, the bucket having the reduced cylindrical extension with the ring about the 50 lower edge thereof projecting annularly about the cylindrical extension and having an inwardly-projecting valve-seat rim, said cylindrical extension also having a cross-bar and laterally and outwardly extending pivot-pins, 55 the valve seated on the inwardly-projecting rim and having an upwardly-extending stem guided in the cross-bar and the driving-yoke engaging the pivot-pins on the outside of the reduced extension, substantially as described. 60

Signed at Glasgow, Scotland, this 17th day of January, A. D. 1896.

ALEXANDER SHIELS.
